(57) **CLAIM**

The design for an inflation system for sealed air devices, as shown and described.

DESCRIPTION

FIG. 1 is a side perspective view showing a sealed air device with the rapid inflation feature;

FIG. 2 is a rear elevation view thereof;

FIG. 3 is a front elevation view thereof;

FIG. 4 is a top plan view thereof;

FIG. 5 is a bottom plan view thereof;

FIG. 6 is a left elevation view thereof;

FIG. 7 is a right elevation view thereof;

FIG. 8 is a side perspective view showing a sealed air device with the rapid inflation feature partially coiled; and,

FIG. 9 is a side perspective view showing a sealed air device with the rapid inflation feature secured behind a closure.
